(57) **CLAIM**

The ornamental design for a framing profile, as shown and described.

DESCRIPTION

FIG. 1 is a left side perspective view of a framing profile showing our new design.

FIG. 2 is a right side perspective view thereof.

FIG. 3 is a left side perspective view of a second embodiment of a framing profile.

FIG. 4 is a right side perspective view thereof.

FIG. 5 is a right side perspective view of a third embodiment of a framing profile.

FIG. 6 is a left side perspective view thereof.

FIG. 7 is a right side perspective view of a fourth embodiment of a framing profile; and,

FIG. 8 is a left side perspective view thereof.

The framing profiles contain solid core elements of, for example, a foamed insulating material.
